UNITED STATES PATENT OFFICE

SOPHUS P. JENSEN, OF SAN FRANCISCO, CALIFORNIA.

COMBINED MERRY-GO-ROUND AND SKATING-RINK.

1,097,026.

Specification of Letters Patent. Patented May 19, 1914.

Application filed October 29, 1913. Serial No. 798,368.

To all whom it may concern:

Be it known that I, SOPHUS P. JENSEN, a citizen of the United States, residing at San Francisco, in the county of San Francisco and State of California, have invented 5 certain new and useful Improvements in Combined Merry-Go-Rounds and Skating-Rinks; and I do hereby declare the following to be a full, clear, and exact description 10 of the invention, such as will enable others skilled in the art to which it appertains to make and use the same.

This invention relates to amusement devices and one of the principal objects of the 15 same is to provide a combined merry-go-round and skating rink, which will serve to teach persons to skate and which will at the same time serve as an amusement device for a number of auditors and will also 20 accommodate a number of persons who desire to take a circular ride similar to one upon a merry-go-round.

Another object of the invention is to provide means to support skaters, learning to 25 skate, by means of a swing bar, supported by ropes or chains from a rotating carrier so that the skaters will move around the floor and at the same time be supported and be prevented from falling or injuring them- 30 selves.

These and other objects may be attained by means of the construction illustrated in the accompanying drawings, in which,

Figure 1 is a vertical sectional view taken 35 through the floor and a portion of the auditorium and showing in elevation the center pole and the cars or carriages and the skaters' support, and Fig. 2 is a horizontal sectional view taken on the line 2—2 of Fig. 40 1, looking in the direction indicated by the arrows.

Referring to the drawings the numeral 1 designates the casement and machinery pit, 2 the walls and 3 the ceiling of a building 45 for containing the amusement device. A center pole 4 is mounted at its lower end in a block 5 and may be provided with a conical end 6, to fit a conical socket in the block 5. Secured to the pole 4 is a friction disk 50 7 and for rotating this disk a shaft 8 is provided journaled in hangers 9, secured underneath the floor 10 and provided with a pulley 11 which may be connected to any suitable motor or source of power. The upper 55 end of the pole 4 is mounted to rotate in a bearing block, or plate, 12, secured to the

ceiling 3. Secured to the pole 4 to rotate therewith is a plurality of braces 13 connected at their upper ends to a circular plate 14 and the lower ends of said braces are 60 connected to lugs secured to the outer ends of arms 15, said arms being secured to the pole 4, by means of spaced plates 16. Connected to the lugs 17 at the ends of the arms 15, are the supporting rods 18 for the carriages 19, designed for the purpose of seating several passengers. Connected to the carriages 19 in any suitable manner are flexible members 20 which carry at their lower ends horizontal bars 21 and the members 20 may be readily adjusted so that persons grasping the rods 21, or bars, may be supported while skating upon the floor 10. 70

A stairway 22 leads up to the spiral staircase 23 which serves to land the passengers 75 or auditors upon the floor 24, upon which floor may be located a band of music and attendants to assist the passengers to the cars or carriages 19.

Persons desiring to skate may get off upon 80 the floor 10 and if they are learning to skate they may grasp the horizontal bars 21 and be carried around with the carriages 19. The floor 24 is supported upon uprights 25.

Balconies for visitors provided with seats 85 26 may be provided to substantially surround the amusement device, and the seats 26 may be supported upon floors 27 obtained by means of uprights or walls 28. Stairways 29 may be provided to admit the visitors to the seats 26.

From the foregoing it will be obvious that persons learning to skate may grasp the bars 21 and be carried around by the merry-go-round, and that the bars 21 may be adjusted 95 in any suitable manner to conform to the height of the person learning to skate. Persons desiring to ride in the carriages 19 may pass up the spiral staircase 23 and be assisted into the carriages by attendants.

It will be apparent from the foregoing 100 that an amusement device made in accordance with my invention will serve to instruct persons in skating and at the same time provide amusement for a great many persons.

What is claimed is:

1. An amusement device comprising a center pole, means for rotating said pole, arms connected to said pole and rotated therewith, carriages for passengers supported upon the outer ends of said poles, horizontal bars adjustably supported underneath 110

said carriages for the accommodation of skaters, and a floor for the skaters.

2. An amusement device of the character described comprising a center pole mounted to rotate in a base, means for rotating said pole, arms connected to said pole to rotate therewith, means for supporting carriages connected to said arms, carriages connected to said means, horizontal bars supported from said carriages for skaters, a floor for

said skaters, a spiral stair-case, a floor for the passengers for said car disposed above the skaters' floor.

In testimony whereof I affix my signature in presence of two witnesses.

SOPHUS P. JENSEN.

Witnesses:

C. S. CLEMENS,
N. S. THOMPSON.
